(57) **CLAIM**

The ornamental design for an oval shaped condenser unit, as shown and described.

DESCRIPTION

FIG. 1 is a front perspective view of an oval shaped condenser unit showing my new design;

FIG. 2 is a rear perspective view thereof;

FIG. 3 is a side perspective view thereof;

FIG. 4 is a front elevational view thereof;

FIG. 5 is a rear elevational view thereof;

FIG. 6 is a left side elevational view thereof;

FIG. 7 is a right side elevational view thereof, showing the plane upon which a cross sectional view is taken show in FIG. 8;

FIG. 8 is a cross section view thereof taken along line 8-8 of FIG. 7;

FIG. 9 is a bottom plan view thereof; and,

FIG. 10 is a top plan view thereof.
